UNITED STATES PATENT OFFICE.

GUY W. SMITH AND LUTHER DINSMOOR, OF PAONIA, COLORADO.

GRAIN-SHOCKING MECHANISM.

1,268,169.

Specification of Letters Patent.

Patented June 4, 1918.

Application filed October 25, 1916. Serial No. 127,614.

To all whom it may concern:

Be it known that we, GUY W. SMITH and LUTHER DINSMOOR, citizens of the United States, residing at Paonia, in the county of Delta and State of Colorado, have invented certain new and useful Improvements in Grain-Shocking Mechanism; and we do hereby declare the following to be a full, clear, and exact description of the invention, such as will enable others skilled in the art to which it appertains to make and use the same:

This invention relates to grain shocking mechanism, and more particularly to shocking mechanism carried thereby, for shocking bundles of grain, such as wheat, oats, rye, barley and the like.

Another object of the invention is the provision of simple and improved means for transferring the bundles from the point of delivery by the binding mechanism of the harvester to the mechanism of the shocker.

Another object of the invention is the provision of shocking mechanism that is attached to, supported and operated by the mechanism of any approved modern harvester.

Another object of the invention is to provide shocking mechanism which will be automatic in its entire operation.

Another object of the invention is to provide a shock former mounted upon a carriage, and novel means for automatically moving the carriage backward and forward from shock receiving position to shock discharging position.

Another object of the invention is to provide a shock former disposed in horizontal position and which when filled is immediately raised to a vertical position and then carried in said position to a shock discharging position.

Another object of the invention is the provision of novel means for discharging the shock from the former to the ground so that the shock will settle thereon in an upright position.

A further object of the invention is the provision of a shock former embodying a plurality of pivotally mounted radial arms and means for spreading the arms from beneath the shock to allow the shock to drop to the ground.

A still further object of the invention is

to provide means to carry the shock former rearwardly of the binder at a speed equivalent to the speed at which the machine is carried forward in cutting the grain, so that at the time the shock is released the shock is relatively at rest.

A still further object of the invention is the provision of means for turning the bundles as they slide from the binder deck so that they drop into the shock former with their flat sides to the center of the shock.

With these and other objects in view as will appear as the description proceeds, the invention comprises the various novel features of construction, the combination and arrangement of parts as will be more fully described hereinafter and set forth with particularity in the appended claims.

Referring to the drawings,

Figure 1 is a side elevation of a harvester machine showing our improved shocking mechanism attached thereto.

Fig. 2 is an end view of the shocking mechanism and of the means for attaching and supporting the same upon the binder.

Fig. 3 is a side elevation of a portion of the binder showing our improved shocking mechanism in discharging position.

Fig. 4 is a fragmentary side elevation of the binder showing the slidable frame and the movable carriage connected thereto in the act of moving forwardly of the machine.

Fig. 5 is a similar view to Fig. 4 showing the movable frame and the carriage together with the shock former supporting arm in the limit of their forward movement.

Fig. 6 is an enlarged sectional plan view of the movable carriage and the supporting means therefor.

Fig. 7 is a longitudinal sectional view taken on the line 7—7 of Fig. 6 looking in the direction of the arrow.

Fig. 8 is a sectional end elevation taken on the line 8—8 of Fig. 6 looking in the direction of the arrow.

Fig. 9 is a transverse sectional view on the line 9—9 of Fig. 4 looking in the direction of the arrow.

Fig. 10 is a vertical sectional view of the upper portion of the shock former, showing the shock embracing arms moved to open or discharge position by dotted lines.

Fig. 11 is a sectional plan view taken on the line 11—11 of Fig. 10.

Fig. 12 is a similar view to Fig. 11 showing the ratchet mechanism in the act of being reset.

Fig. 13 is a sectional plan view on the line 5 13—13 of Fig. 10.

Fig. 14 is a sectional plan view on the line 14—14 of Fig. 10, and

Fig. 15 is a diagrammatic plan view of 10 the shock former, showing the method of operation of the spreader arms.

Similar characters of reference are used 15 to denote like parts throughout the accompanying drawings.

Referring more particularly to the drawings 20 the letter A represents a harvester machine and binder of any well known approved modern construction which embodies the usual supporting frame structure B to which is attached my improved shocking mechanism C.

Track rails 1 and 2, which in this instance 25 are shown to be of I beam construction and formation, are disposed longitudinally of one side of the harvester machine and below 30 the binder deck plate thereof. These track rails are rigidly supported in a parallel horizontal position with respect to one another through the medium of suitable braces 3 which are secured to the harvester frame structure B in any suitable manner.

Mounted upon the track rail 2 is a slide- 35 able frame 4, the opposite ends of which are shown to embrace the track and its flanges so as to firmly support the frame member in a vertical position and yet allow 40 of a free sliding movement backward and forward upon the track. As clearly shown in Fig. 4 of the drawings the slideable frame 4 is shown to consist at its forward end of a vertically disposed frame bar 5, the lower 45 end of which embraces the upper flange of the rail 2 as indicated at 6, while the upper end of the bar 5 is offset as indicated at 7, and securely attached to the under side of the movable binder deck 8, so that it will 50 slide with the binder deck when it moves forward and backward, in order that the shock former will always be in proper position to the bundle tying needle. Secured to 55 the bottom portion 6 of the bar 5 is a horizontally extending stop arm 10, which extends rearwardly of the arm and is curved downwardly as indicated at 11 to form an effective stop, for a purpose which will pres- 60 ently appear. The rear portion of the frame embraces the track rail 2 as indicated at 12 and then extends upwardly and forwardly in the form of a supporting bar 13, which extends forwardly above and in substantially 65 parallel relation to the track 2, and then extends upwardly to a point adjacent the bar 5, where it is provided with an offset flange 14 similar to the flange 7 that is designed to be attached to the underneath surface of the 65 sliding binder deck. An arcuate bar 15 ex-

tends downwardly and forwardly from the flange 14 and is connected to the bar 5 intermediate its ends. The rear portion of the bar 13 is provided with an upwardly extending curved arm 16, that is also offset at its 70 upper end and is secured to the binder deck 8. At the juncture of this arm 16 with the bar 13, there is formed a recess 17 for a purpose which will presently appear.

Mounted upon the inner face of the frame 75 4 is a horizontally disposed rock shaft 18, that is journaled in suitable bearings 19. The rocker arm 20 is fixed upon the shaft 18 and has connected to its inner end the rod 21, which is connected at its opposite 80 end to a crank arm 22 fixed upon the needle shaft 23, that is common to any harvester of modern construction. The opposite end of the rocker arm 20 is offset laterally and provided with a roller 24. From this it will be 85 seen that every time the needle shaft is rocked, in the operation of tying a bundle of grain, the rocker arm 20 will likewise be given a rocking movement corresponding to the tying of each bundle. 90

A carriage D is mounted upon the track rails 1 and 2 for movement backward and forward of the length of the machine. This carriage is shown to consist of a cross bar 25 at the rear end thereof which is connected 95 to supporting hangers 26 and 27. Journaled in the upper and lower ends of the hanger 26 are flanged supporting wheels 28, that have their opposite ends connected together by a brace bar 29 so as to hold and retain 100 these flanged wheels upon the track rail 1.

The inner forward portion of the carriage is supported by flanged wheels 30 that are journaled in the opposite ends of a hanger 31, while the opposite journal ends of the 105 wheels 30 are supported in a bracket 32 that is connected to the bar 29 of the brace bar 33.

A rocker shaft 34 extends transversely of the carriage and has one of its ends journaled in the hanger 31 and its opposite end journaled in the end of a supporting arm 35 which extends longitudinally of the frame and is rigidly secured to the cross bar 25. 110

Mounted upon the inner end of this rock shaft is an enlarged rocker arm which is 115 shown to consist of arms 36 and 37, the outer ends of both arms being provided with friction rollers 38 and 39.

As shown the harvester A is shown to embody a revolving shaft 40 which is of ordinary and well known construction used in connection with the mechanism for driving the conveyer mechanism, as indicated clearly in Fig. 2 of the drawings. This shaft 40 extends longitudinally of the binder and has 120 mounted thereon a worm hub 41, that is provided with a set of worm threads formed in two different pitches 42 and 43, one of which is a continuation of the other.

The friction rollers 38 and 39 are designed 130

and adapted to engage this set of worm threads, during the movement of the carriage from an extreme front to an extreme rear position. As shown the worm threads 42 have a very slight pitch, while the threads 43 have a greater pitch, by which it will be seen that as the friction roller 38 engages the threads 43, in the movement of the carriage from the front to the rear of the machine, that the carriage will travel back equivalent to the speed at which the harvester is traveling forward until the roller has reached the end of the threads 43, where the roller 39 will be disengaged and from this it will be seen that the movement of the carriage rearwardly will be relatively at a stand still with respect to the forward movement of the harvester.

As shown the worm hub consists of two spiral thread pitches 43 which extend oppositely around the hub 41 to drive the carriage in opposite direction.

In order to drive the carriage forward the friction roller 38 is adapted to first engage the worm thread pitch 42 and then the thread 45, and after the carriage has reached the limit of its forward movement, the rocker arm 37 is rocked downwardly so that the friction roller 39 will engage the worm thread 46, from which it will be seen that the same continued rotation of the worm hub 41 will be used to drive the carriage rearwardly to the limit of this movement, or in other words to a shock discharging position. As the thread 42 is of such a slight pitch it will be apparent that the car will move forward at a very slow rate of speed in order that the shock former arms will have time to pass over the shock before being closed.

Extending transversely of the carriage D is a rock shaft 47 which has its inner end journaled in the frame bar 35 and its outer end supported in the triangular hanger 27 and the connecting bar 48. The outer end of this rock shaft 47 is formed with the right angular extension trip arm 49 that extends forwardly of the carriage, and is designed to be tripped or moved upwardly to swing the friction pulley 39 downwardly into engagement with the worm thread 46 in order to move the carriage rearwardly of the machine.

The outer side of the carriage D is supported upon the track rail 2 for movement by flanged rollers 50 that are journaled between and in the opposite ends of the triangular hanger 27 and the connecting bar 48. Journalized in the lower end of the triangular hanger 27 is a flanged roller 51 which bears and rides on the underneath surface of the track rail 2 in order to retain the carriage in position upon the track rails at all times under various conditions that may exist in the operation of the shocker.

Mounted upon the rock shaft 47 is a rocker arm 52 which extends forwardly thereof and is connected by a link 53 to the arm 54 of a substantially T shaped trip arm, which latter is fixed upon the rock shaft 34. 70 This trip arm embodies additional arms 55 and 56, the arm 56 extending oppositely to the arm 54, and has connected to its outer end a link 57, the opposite end of which is connected to one end of a retractile spring 75 58, which in turn is attached to the cross bar 25 of the carriage.

From the relative position of the parts shown in Fig. 7 of the drawings, it will be manifest that the retractile spring 58 exerts 80 an upward tension on the arm 56 of the T shaped trip arm, which in turn has the tendency to rock the shaft 34 and thereby cause the friction roller 38 carried by the arm 36, which is secured to the opposite end 85 of the shaft 34, to be held in engagement with the worm thread 45.

By the time that the carriage has reached the limit of its forward movement, or in other words a shock receiving position, the 90 friction roller 59 carried by the end of the arm 55 will have engaged beneath the release trip 60 mounted upon the binder arm and ridden down the inclined face 61 thereof of a sufficient distance to rock the arm 55 95 downwardly and rearwardly and consequently move the friction roller 38 upwardly out of engagement with the thread 45, to a position substantially as shown. When the parts are in the position shown in 100 Fig. 7, it will be apparent that neither of the friction rollers 38 or 39 are in engagement with the worm threads, from which it will be apparent that the carriage will remain at rest until a sufficient number of 105 bundles of grain have been deposited within the shock former to form a complete shock.

Immediately after the completion of the formation of the shock, the trip arm 49 is moved upwardly, which in turn will move 110 the rock arm 52 upwardly, rock the T shaped trip arm until the pivotal center of the connection of the rod 57 with the arm 56 has passed below a line drawn through the rock shaft 34 and the connection of the 115 retractile spring 58 with the frame bar 25. From this it will be seen that when the trip arm 49 has been moved upwardly a sufficient distance, the friction roller 39 will be moved quickly downwardly into engagement with the reverse thread 46 of the worm hub, which will immediately reverse the movement of the carriage and move the same rearwardly into a shock discharging position.

As soon as the carriage has reached a shock discharging position, the friction roller 59 of the arm 55 will engage the inclined face 62 of a stop 63 that is mounted upon the binder frame in a suitable manner. By 130

a slightly further movement of the carriage, or in other words when the carriage has reached the limit of its extreme rearward movement, the roller 59 will have ridden down the inclined face 62 sufficiently to disengage the friction roller 39 from the reverse thread 46 and immediately cause the friction roller 38 to descend into engagement with the thread 42, which will immediately cause the carriage to start forward to its initial shock receiving position.

Extending transversely of the carriage and mounted in bearings 64 upon the cross bar 25 is a shaft 65 which is provided at one end with a bearing flange 66 to which is rigidly connected a supporting arm 67, that extends in angular relation to the shaft 65, and which is designed to support the shock former. If found desirable the shaft 65 may be removed from its bearings by moving the pin 68 which passes through the collar 69 mounted upon the opposite end of the shaft.

Formed integrally with and extending at right angles to the supporting arm 67 is an extension arm 70, the outer end of which is curved arcuately and provided with a friction roller 71 that is designed to engage and ride within an arcuate slot 72 formed in the horizontally extending bar 13 of the slideable frame 4. Secured to the supporting arm 67 adjacent its outer end is a brace arm 73 which is provided at its outer end with a friction roller 74 that is designed to ride down the inclined face 75 and seat within the recess 17 of the slideable frame 4, when the shock former is moved to a receiving position, as clearly shown in Figs. 2, 4 and 5 of the drawings. This arm is intended to help support the weight of the shock former at its outer end.

Referring more particularly to Fig. 10 of the drawings, it will be seen that the upper or outer free end 67 is curved to form an angular extension 76 which has secured thereto a bearing 77 that is provided at its lower end with a circular flange 78.

Extending vertically through the bearing 77 is a vertical movable shaft 79 which has mounted upon its upper end an operating lever 80 which is connected to a belt crank trip arm 81 by a rod 82. This trip arm 81 is provided with a bearing roller 83 that is designed to engage a trip, which will presently be described, in order to cause the shaft 79 to move vertically through the bearing 77. This trip arm 81 is pivotally mounted upon an extension 84 of the supporting arm 67.

The vertically movable shaft 79 is provided with a slot 85 into which projects a set screw 86, that is threaded through the upper end of the bearing 77, and which is designed to limit the vertical movement of the shaft 79.

Attached to the under face of the circular

flange 78 by bolts or screws is a circular cavity 88, in which is seated for rotation an annular ring 89 that is connected to the upper end of the sleeve 90 that is formed centrally upon a hood 91, by suitable screws 70 or bolts. As shown the hood 91 is circular in cross section and the walls extend downwardly and outwardly to provide an inclined surface 92, the lower end of the circular wall is then formed to extend vertically downward so as to provide an annular shoulder 93. A head block 94 having a plurality of radial arms 95, as shown in Figs. 10 and 13 is disposed within the hood 91. Each of these arms 95 are provided with slots 96 in 80 which are pivotally mounted, as indicated at 97 the upper ends of the shock former arms 98.

As clearly shown in Fig. 10 of the drawings, these arms are formed to provide substantially vertical extensions 99 that are designed to conform in shape to the inner surface of the hood 91 and when in their normal position are designed to lie flush therewith. These extensions 99 are formed integrally 90 with a horizontally extending portion 100 that extends radially to a point beyond the hood 91, where they are connected to the arm 101 that extends downwardly and outwardly and are provided at their lower ends 95 with inwardly and radially extending supporting arms 102, which are of substantially rectangular frame like formation, and are designed to support the butt ends of the shock positioned within the former. Each 100 of the arms 101 are provided adjacent their lower ends with inwardly and radially extending separator arms 103, that are designed to separate and hold the bundles in the relative position shown in Fig. 15 of 105 the drawings by dotted lines.

Extending longitudinally of each arm 101 and journaled in bearings 104 thereon is a rocker rod 105. Arranged upon each rocker rod 105 in spaced relation, and adjacent the lower end thereof, is a pair of clamping arms 106 and 107. Each of the clamping arms 106 has one end of a retractile spring 108 connected to it, while the opposite end of the spring is connected to 115 the inner radial end of the supporting arm 102. The normal tendency of this retractile spring 108 is to swing the clamping arms into the clamping position around the bundles of grain that have been deposited with in the shock former and remain in such position until the shock former has been arranged in discharging position, when these clamping arms are automatically opened and disengaged from the shock.

The upper end of each shock former arm is provided with a right angular extension arm 109 that carries a friction roller 110 at its inner end.

Mounted upon the lower end of the ver- 130

tically movable shaft 79 is a cam plate 111, that is of substantially circular formation, as will be clearly seen by reference to Fig. 14 of the drawings. This cam plate 111 is 5 provided with an upwardly and inwardly inclined flange 112, which is designed to be engaged by the friction rollers 110. As clearly shown in Fig. 14 of the drawings, the inclined flange 112 is cut away to provide 10 an entrance opening 113. The cam plate 111 is provided with an offset right angular cam flange 114 that is formed integrally with the cam flange 112 at one end, and terminates at its offset end adjacent the 15 entrance opening 113.

As the shock former is rotated, in filling it, the cam rollers which are all on the outside of the cam flanges 112 and 114 will consecutively enter the passage 113, after the 20 bundles have been placed within each compartment of the shock former, by virtue of the retractile springs 108, until each and every one of the cam rollers 110 have entered and are positioned entirely within the 25 cam flange 112. The last of the cam rollers positioned upon the outer surface of the cam flange 112 will enter the passage 113 immediately after the last bundle of grain has been dropped into position within the shock 30 former. By each and all of these cam rollers entering within the circumference of the cam flange 112 it will be apparent that as each one does, the clamping arms 106 and 107 will be swung from an open position 35 into a clamping position around the bundles contained within the shock former.

By reference to Figs. 14 and 15 of the drawings, it will be obvious as each cam roller 110 passes around the outer surface 40 of the flange 112, that they will consecutively ride outwardly and around the extension cam flange 14, so as to open the clamping arms 106 and 107 the full limit of their movement in order that the bundle or 45 bundles may be quickly and readily dropped into position within the shock former.

Again referring to Fig. 10 of the drawings it will be seen that the head block 94 is provided with a tubular sleeve 115 which is 50 slidably mounted upon the shaft 79 between the cam plate 111 and a collar 116 keyed to the shaft and disposed within the recess 117 formed in the upper portion of the head block. The sleeve 115 is provided intermediate its length with a circular flange 118 that is provided with a peripheral upstanding flange 119, which is designed to bear 55 against the inner surfaces of the shock former arms, or the vertical extensions 99 thereof, and to hold the same in a rigid position against the inner inclined surfaces 92 of the hood 91.

Each of the shock former arms 101 has a rod 120 connected to the horizontal portion 60 100 and projects upwardly through an open-

ing in a supporting lug or plate 121 that projects laterally from the hood 91. The upper free end of each of these rods 120 is threaded and is provided with a ball bearing member 122 which is held thereon by a 70 nut 123.

In the operation of the shock former in the act of discharging the bundle from the shock former, and bearing in mind the fact that all of the cam rollers 110 are positioned 75 within the cam flange 112, the initial movement in the device is for the shaft 79 to move downwardly until the stop collar 116 rests upon the upper end of the tubular bearing 115, from which it will be seen that this 80 movement is sufficient to disengage the cam flange 112 from the cam rollers, and which by a further downward movement will cause the peripheral flange 119 to be disengaged from the vertical extensions 99. After this 85 initial movement takes place, the continued movement of the shaft 79 will force the head block 94, together with the bearing sleeve 115 downwardly until the bearing balls 122 rest upon the supporting brackets 121, after 90 which by a continued downward movement of the shaft 79 the arms 101 will be forced outwardly so as to disengage the supporting arms 102 from beneath the shock, as clearly shown by the dotted lines in Fig. 10. These 95 bearing balls 122 act as fulcrums on which the levers are swung outwardly.

Immediately after the shock has been discharged from the shock former, the shaft 79 moves upwardly, the first initial movement 100 of which carries the cam plate 111 to a position so that when by a further upward movement, the shock former arms 101 are swung inwardly, the cam rollers 110 will engage the outer surface of the peripheral flange 105 112. As the shaft 79 moves upwardly to the limit of its movement, or to its normal position, the cam rollers 110 will move around the flange 112, thus rocking the right angular extension arms 109 outwardly sufficiently 110 to allow the shock former arms to move inwardly to their initial position, which also at the same time cause the clamping arms to immediately open, which latter are fully open when they pass around the 115 extension cam flange 114.

Again referring to Figs. 13 and 15, it will be noted that our improved shock former is shown to consist of a plurality of radial extending arms, which are pivotally mounted 120 in the head block 94 preferably, as shown, the shock former consists of six radial arms, two of these arms are so constructed that when positioned within the head block, they will lie in direct alinement with one another. 125 Each pair of arms that is disposed on opposite sides of the alining arms are offset laterally in opposite directions to provide a double bundle receiving space therebetween, and also to provide a single bundle receiving 130

space between each of these offset arms and each of the alining arms. From this it will be seen, by reference to Fig. 15 that the shock former is designed to receive eight bundles of grain, as clearly indicated by the dotted lines, each bundle being dropped into the shock former in such a manner that the flat sides thereof will be positioned innermost of the shock.

- 10   Mounted upon the top of the hood 91, is a double ratchet wheel 124 which is provided in its peripheral edge with two sets of ratchet teeth 125 and 126, the teeth of one ratchet being disposed and formed 15 versaely of those of the opposite ratchet. This ratchet wheel 124 is provided centrally with an opening 127 in which is mounted a circular head plate 128 that is provided with a central opening designed to receive 20 the tubular bearing sleeve 90. This head plate is provided with oppositely extending arms 129 and 130, whereby the head plate may be rotated. The arm 129 has connected to it a retractile spring 131, which latter is 25 connected to a bracket arm 132 that is secured to the shock former supporting arm 67. The arm 130 is provided with a ratchet pawl 133 and is designed to lockingly engage the ratchet teeth 125, as clearly shown 30 in Fig. 12 of the drawings.

Rotatably mounted upon this head plate 128 is an additional head plate 134 and is formed with a trip arm 135, the outer end of which extends in angular relation to the 35 arm as indicated at 136 and is provided with a trip lug 137 which is pivotally mounted in the end thereof, said lug being only movable outwardly of the extension 136, and designed to engage a stop shoulder 40 when moved in the opposite direction in order to retain it in the position shown now. This trip arm 135 lies in the same plane with the arm 130 and is disposed directly 45 behind it. Pivotally connected to the outer end of this trip arm 135 is a rod 138 that is in turn connected to an arm 139 that is fixed to a rock shaft 140, which latter is journaled in one end of the bracket 132. This shaft 140 is journaled at its opposite end in a 50 bearing 141 secured to the supporting arm 67 adjacent its pivotal connection with the carriage D. The lower end of this rock shaft 140 is provided with a bifurcated rocker arm 142, one of the arms 143 formed 55 by the bifurcation being curved upwardly and inwardly, as clearly indicated in Fig. 9 of the drawings to provide a bearing surface whereby the friction roller 24 carried upon the outer end of the rocker arm 20 60 will positively engage the arm 143 and ride into the bifurcation of the arm 142. In other words the arm 143 is so shaped that in case it has moved down to any position of its range of movement by the starting of 65 the needle to form a new bundle before the

form has fully returned to position to receive the bundle, the arm will automatically adjust itself to a position to receive the friction roller 24 of the rocker arm 20.

Extending radially from the housing 87 70 and in opposite directions are arms 144 and 145, the arm 144 being provided in its outer end with the pawl 146 that is designed to engage the ratchet teeth 125, while the outer end of the arm 145 carries the pawl 147 having a trip shoulder 148 that is designed to engage the ratchet teeth 126.

This ratchet mechanism is designed for the purpose of rotating the shock former 80 one notch at a time so as to receive the bundles consecutively one after the other until eight bundles have been tripped into the shock former. It is to be noted that there is a ratchet tooth in the ratchet wheel for every 85 bundle to be deposited within the shock former.

In the operation of this ratchet mechanism and by particular reference to Fig. 11 of the drawings, it will be seen that the parts are so positioned to indicate that the shock former has received a bundle, and rotated sufficiently to receive an additional bundle. As the bundle tying needles are projected through the deck plate 8 of the binder in the operation of tying a bundle, 95 the needle shaft 23 will be locked, which in turn will pull on the rod 138, this movement drawing the trip arm 135 over toward the left, which latter being in the same plane with the arm 130 will move it over to the 100 left until the ratchet pawl 133 engages the first ratchet tooth 125, this operation extending the retractile spring 131 connected to the arm 129. After the bundle tying needle has performed its function and moved 105 back through the deck plate 8, a reverse motion will be imparted to the rod 138, which will move the trip arm 135 over to the dotted line position shown in Fig. 12 of the drawings. As the trip arm 135 moves 110 over to this dotted line position, the trip lug 137 will engage the shoulder 148 of the pawl 147 and release the latter from the ratchet tooth 126. As soon as this ratchet pawl 147 has been released from the tooth 115 126, the retractile spring 131 will immediately retract and rotate the ratchet wheel in the direction of the arrow a distance sufficient to receive an additional bundle in the shock former. This action of the spring 120 131 will bring the parts into the same relative position as shown in Fig. 11 of the drawings, since the pawl 146 is pivotally mounted to the fixed arm 144, it will be apparent that this pawl holds and retains 125 the ratchet wheel against movement in one direction while the arm 130 is being returned, and by the trip arm 135, to its initial operative position to enable the pawl 133 to engage the next preceding tooth. 130

It is to be noted that the ratchet wheel is provided with a pair of ratchet teeth that are automatically opposite, and which are designed to be in the same relative alinement 5 with each pair of shock former arms that are bent laterally and opposite to one another to provide a double bundle receiving space therebetween. When this double bundle receiving compartment rolls around into 10 bundle receiving condition, the operation to rotate this particular compartment a short distance twice to receive two bundles, will be substantially the same as when the ratchet wheel is rotated a distance sufficient to receive a single bundle. In the operation in 15 this instance, the arm 130 carrying the pawl 133 will be moved over beyond the second tooth of the particular pair of teeth to the full extent of its movement. This being 20 done and there being no tooth for the pawl 133 to immediately engage, the spring 131 will move the pawl 133 around the periphery of the ratchet wheel until it engages the second tooth of the particular pair of 25 teeth in question, from which it will be seen that the pawl 133 will simply rotate the ratchet wheel of one ratchet tooth, or a distance sufficient to receive the second bundle in the double bundle receiving compartment 30 of the shock former.

In the operation of the device and referring more particularly to Figs. 1 and 4 of the drawings, the shock former which is supported by the movable carriage D, together with the sliding frame 4 are shown 35 in the act of moving forwardly of the harvester to a shock receiving position.

In Fig. 5 of the drawings the carriage together with the sliding frame has been 40 shown in shock receiving position, or in other words in the limit of its forward movement, and is urged to start on its inner rearward movement. The limit of the first initial rearward movement of the carriage 45 carrying the shock former supporting arm and operation of the latter is indicated by the dotted lines shown in the above mentioned Fig. 5.

Briefly describing the operation of our 50 improved shocking mechanism, the shock former is positioned forwardly of the harvester as indicated by the position of its supporting carriage shown in Fig. 5 of the drawings. Assuming the shock former to 55 be in this position, it is rotated step by step by the ratchet mechanism arranged upon the top of the hood 91 through the medium of its connection with the needle rock shaft 23, clearly shown in Fig. 2 of the drawings.

In the operation of the harvester and 60 binder, the bundle tying needle passes through the binder deck plate and ties a bundle of grain, after which the bundle is discharged downward to the inclined deck 65 plate into one of the compartments of the

shock former. Immediately after this bundle has been tied and placed within the shock former, the bundle tying needle moves back through the deck plate, and as a result rocks the needle shaft 23 which by its connections with the rocker arm 20 through the medium of the link 21, will cause the rocker arm 20 to move upwardly at its inner end and downwardly at its outer end. This downward movement of the outer end of the 70 rocker arms 20, will cause the friction roller 24, Fig. 9, to descend upon the curved upper face of the arm 143 and ride into the bifurcation of the rocker arm 142, and which by a continued downward movement will cause 80 the shaft 140 to rock in its bearings and move the rod 138 inwardly through the medium of the arm 139. This rod 138 being connected to the trip arm 135 of the ratchet mechanism will cause the ratchet wheel 121 85 to rotate one step, or a distance sufficient to receive one bundle of grain. From this it will be seen that immediately after each bundle has been tied and deposited in the shock former, the receding action of the bundle 90 tying needle will cause the shock former to rotate one step, or to a position to receive another bundle.

As the shock former rotates, the cam rollers 110 will ride over the cam flange 114 95 which will cause the clamping arms 106 and 107 of each compartment to fully open to receive the bundle or bundles, depending upon the compartment that happens to be in bundle receiving position. After the 100 bundle has been deposited in its particular compartment and the shock former has been rotated one step, the cam roller governing clamping arms of that particular compartment will ride around the cam flange 114 105 until it comes into communication with the passage 113, where the cam roller will be immediately forced through the passage 113 to a position on the inside of the cam flange 112, through the medium of the retractile 110 spring 108, which will in turn cause the clamping arms 106 and 107 to automatically close and clamp the bundle or bundles into the particular compartment. This operation as above described takes place consecutively until the shock former has been filled with bundles, or in other words until eight bundles have been deposited therein.

As soon as a bundle has been deposited in the last vacant compartment of the shock former, a trip arm 149 attached to the arm 101 of this last compartment, will move upwardly, as will be understood by reference to Fig. 1 of the drawings, into engagement with the trip arm 49. The upward movement of this trip 49 will rock the shaft 47, move the arm 52 upwardly, which in turn will rock the shaft 34 causing the bearing roller 39 carried by the arm 37 to descend 125 downwardly into engagement with the worm 130

thread 36 of the worm hub 41, which will immediately cause the carriage D carrying the shock former to immediately move rearwardly to a shock discharging position.

5 Referring to Fig. 5 of the drawings it will be seen that in the first initial rearward movement of the carriage that the friction roller 71 carried by the extension arm 70 of the supporting arm 67, will ride 10 down the arcuate slot 72 in the slidable frame 4, it being understood that at the same time that this roller 71 is moving downwardly that the carriage is moving rearwardly beneath the roller 71, so that 15 by the time the carriage has moved rearwardly a sufficient distance to cause the roller 71 to have moved to the end of the slot 72, the supporting arm 67 will have been caused to move to a vertical position 20 as indicated by the dotted lines. This movement is accomplished very quickly owing to the great degree of pitch of the worm thread 43.

As soon as the shock former has been 25 moved to this upright position it is carried on rearwardly to a shock discharging position by the worm thread 43, and at the same relative speed at which the harvester machine moves forward in the operation of 30 harvesting the grain.

Just before the bearing roller 39 has reached the end of the thread 43, the friction roller 83 carried by the trip arm 81 will come into engagement with the downwardly and arcuately inclined flange 150 of 35 a trip plate 151 which is fixed to the web of the track rail 2 in any suitable manner. By a continued rearward movement of the carriage the friction roller 83 will move 40 down the surface of the flange 150 sufficiently far to rock the trip arm 81 and hold down upon the rod 82, which in turn will cause the shaft 79 to descend vertically through the medium of the arm 80 connect- 45 ed thereto. This descending movement of the shaft 79 will cause the shock former arms to be released and spread radially and outwardly to disengage the supporting arms 102 and the separator arms 103 from the 50 shock, thus allowing the shock to drop a short distance to the ground, so as to settle the bundles together.

By the time that the roller 39 has reached the end of the thread 43, the shock will have 55 been discharged, the roller 39 disengaged and the roller 38 engaged with the thread 42, which particular set of threads will cause the shock former to move forwardly, and we will say for the purpose of illustration, 60 the distance of five inches, while the harvester is moving forward a distance of five feet. From this it will be seen that the shock former arms will have plenty of time to pass over the shock before the mecha-

nism to be hereinafter described, proceeds 65 to close the arms.

In the preferred construction of the shock former, it is to be understood that each of the supporting rods 120 increase in length gradually from a position directly in the 70 rear of the shock former, around the circumference of the shock former, so that when the arms are spread from beneath the shock, each arm will consecutively, from a point directly forward of the shock former, 75 and around the circumference thereof, be moved outwardly and upwardly a little more than the preceding arm. From this it will be noted that the rear arms are swung upwardly to a position so as to readily clear 80 the top of the shock that has been dropped to the ground, as the shock former again moves forward to the harvester.

Again referring to Fig. 5 it is to be noted that when the shock former has reached the position shown in dotted lines, and the roller 71 reached the rear end of the arcuate slot 72 that a continued rear movement of the carriage and shock former will move the slidable frame 4 rearwardly to a shock discharging position, as clearly shown in Fig. 90 3 of the drawings, so that the shock former will be in the proper position to the bundle tying needle.

As soon as the shock has been discharged 95 from the former, the shock former arms moved over the top of the shock and moved radially inwardly to a closed position, the shock former immediately begins to descend from a vertical position to a substantially horizontal position, or to the position 100 shown in Fig. 12 of the drawings, this is accomplished by the friction roller 71 riding up the arcuate slot 72 in the slidable frame 40, which frame remains relatively 105 stationary while this movement takes place. As soon as the shock former has reached the horizontal position as shown in Figs. 1 and 4 of the drawings, the carriage together with the frame 4 is moved forwardly of the harvester, through the medium of the thread 43, 110 to a bundle or shock receiving position.

It is to be borne in mind that immediately after the shock former has been moved from a discharging position to a substantially horizontal position, that the friction roller 83 carried by the trip arm 81 comes into engagement with the stop lug 11 115 formed on the member 10, which by its contact with the friction roller 83 holds the 120 shaft 79 in its elevated position, or a position which holds the cam plate 11 in a fixed relative position with respect to the cam rollers 110. As the shock former moves forwardly, or in other words as it is descending to a horizontal position, the friction roller 83 of the trip arm 81, will engage 125 the arcuately curved flange 152 of the trip

plate 151. As the shock former continues forwardly, this friction roller will ride up over the arcuate flange 153, thus rocking the trip arm 81 back to its initial position, which in turn will move the shaft 79 vertically to its normal position. As soon as the shock former has been moved to a horizontal position, the friction roller 83 will have come into contact with the stop 11 and remain in engagement therewith throughout the movement of the shock former to a shock receiving position, and which will serve to hold the shock former arms closed during the operation of dropping the bundles into the shock former.

Attached to the forward end of the harvester machine and extending to one side thereof is an arcuately curved supporting plate 154 that is designed to support the butt end of the bundles forming the shock that has been rocked into the shock former. This supporting plate 154 is provided medially with a longitudinally extending rod or stubble guard 155, which is designed to prevent the stubble from whipping the butt end of the shock.

Referring to Fig. 2 it will be seen that we have provided means to assist in discharging the bundle from the deck plate into the shock former and is shown to consist of a vertically disposed arm 156, pivotally mounted at its upper end to the knoter frame construction 157, which is of the ordinary well known construction. A finger 158 is pivoted intermediate its ends to the lower end of the arm 156, and pivotally connected to the outer end of the finger 158 is a rod 159, which extends upwardly and is pivotally connected to the knoter frame as indicated at 160. As shown the finger 158 is pointed and extends in the direction of the bundle tying needle, so that as the bundles are tied and gravitate down the inclined deck plate, they will come into engagement with the pointed end of the finger 158, which will swing outwardly under the weight of the descending bundle and by virtue of its engagement therewith, cause the bundle to swing outwardly and properly drop into the shock former as it leaves the deck plate.

From the foregoing description, the advantages of construction, and the method of operation will be readily apparent to those skilled in the art to which the invention relates, and while we have described the principle of operation of the invention, together with the device which we now consider to be the best embodiment thereof, we desire to have it understood that such changes may be made as are within the scope of the appended claims.

What we claim is:—

1. The combination with a self binding

harvester, of shocking mechanism comprising a reciprocal carriage, a shock former rotatably mounted and supported by the carriage, said shock former consisting of a plurality of compartments, means for rotating the shock former around its longitudinal axis, and means for moving the carriage forward and backward of the binder.

2. The combination with a self binding harvester, of shocking mechanism embodying a longitudinally movable carriage, a shock former rotatably mounted and supported by the carriage, said shock former consisting of a plurality of compartments, means for rotating the shock former step by step while disposed in a horizontal shock receiving position, and means for moving the carriage from a horizontal shock receiving position to a vertical shock discharging position.

3. The combination with a self binding harvester embodying a rotatable train shaft, of a worm hub fixed on the rotatable train shaft, track rails supported by the harvester train, a carriage movably mounted upon said track rails, power transmitting mechanism coöperating with the worm hub supported by the carriage, stop lugs mounted upon the binder and adapted to actuate power transmitting mechanism to cause the carriage to move in opposite direction, shock former mechanism carried by said carriage, and means connected with the needle shaft of the binder for automatically connecting the shock former mechanism to successively receive the bundles as they are discharged from the binder.

4. In shocking mechanism of the class described, the combination with a rotatable train shaft, of a self binder and harvester, of a worm hub mounted upon the train shaft, said hub being provided with three sets of worm threads, each set being of a greater degree of pitch than the preceding set and increasing in degree of pitch from the rear end through the front end of the shaft, the first set consisting of a low degree pitch left hand thread, and the second and third sets each consisting of a right and left hand thread disposed in overlapping spiral relation to each other.

5. In shocking mechanism of the class described, the combination with a rotatable train shaft of a self binder and harvester, of a worm hub mounted on said train shaft and provided with oppositely extending worm threads, track rails mounted upon the binder, a wheeled carriage mounted upon said track rails, a rock shaft mounted upon the carriage, rocker arms mounted on said rock shaft, a bearing roller carried by each rocker arm and designed to selectively engage said worm threads, and means adapted

to actuate said rock shaft in opposite directions.

6. In shocking mechanism of the class described, the combination with a rotatable train shaft, of a self binder and harvester, of a worm hub mounted on said shaft and having a plurality of threads varying in degree of pitch, track rails extending longitudinally of the binder above the said worm hub, a wheeled carriage mounted on said track rails, a rock shaft mounted transversely of the forward end of the carriage, rocker arms carried by the rock shaft, a bearing wheel carried by each arm and adapted to selectively engage the worm hub threads, and means adapted to actuate said rock shaft in opposite directions.

7. In shocking mechanism of the class described, the combination with a rotatable train shaft of a self binder and harvester, of a worm hub mounted on said train shaft and provided with a plurality of threads of varying degree of pitch, track rails carried by the binder, a wheeled carriage mounted on said track rails, means on said carriage adapted to coöperate with the threads of the worm hub, tripped blocks mounted upon the binder frame, means carried by the carriage adapted to coöperate with the first named means and with the said trip blocks to alternately reverse the movement of the carriage when moving in one direction and to arrest the movement of the carriage in the opposite direction, a trip arm carried by the carriage and operatively connected to the second named means, and means to trip the trip arm to reverse the movement of the carriage.

8. In shocking mechanism of the class described, the combination with a self binder and harvester, of a rotatable worm hub, a wheeled carriage movably mounted on the binder above said worm hub, a rock shaft mounted transversely of the forward end of the carriage, rocker arms carried by the rock shaft, a bearing wheel carried by each arm and adapted to selectively engage the threads of the worm hub, a substantially T shaped trip arm mounted on said rock shaft, a retractile spring connected to the carriage in each of said rock shafts and to the outer end of the forwardly extending arm of the T shaped trip arm, another rock shaft mounted transversely of the rear end of the carriage, an arm extending forwardly of said last named rock shaft, a link connecting said arm with the rearwardly extending arm of the T trip arm, a friction roller carried by the lower free end of the intermediate arm of the T trip arm, and a trip block mounted upon the front and rear of the binder frame and adapted to be engaged by the said friction roller for the purpose set forth.

9. In shocking mechanism, the combina-

tion with a self binder and harvester, of track rails carried thereby, an arched frame slidable on one of said track rails and formed with an arcuate slot, a wheeled carriage mounted upon said rails and projecting through beneath the arched frame, a shock former supporting arm rotatably mounted upon the said carriage, an extension arm carried by the supporting arm and projecting through said arcuate slot, and means to propel the carriage rearwardly and forwardly of the harvester, the initial movement of the carriage rearwardly causing the extension arm to coöperate with said arcuate slot to raise the supporting arm from a horizontal position to a vertical position, a further movement causing the carriage and extension arm to coöperate with said slidable frame and move the frame to the rear.

10. In shocking mechanism, the combination with a self binder and harvester, of track rails carried thereby, an arched frame slidable on one of said track rails and formed with an arcuate slot in the forward end portion thereof, a wheeled carriage mounted upon said rails and coöoperating with the arched frame, a shock former supporting arm mounted upon said carriage, an extension arm carried by the supporting arm and projecting through said arcuate slot, and means to propel the carriage in opposite directions, the initial movement of the carriage rearwardly causing the extension arm to coöperate with said slot to raise the supporting arm from a shock receiving position to a vertical position, and a further movement causing the carriage and extension arm to coöperate with the slidable frame to move the same to a shock discharging position.

11. In shocking mechanism, the combination with a self binder and harvester, of track rails carried thereby, an arched frame slidable on one of said track rails and formed with an arcuate slot in the forward end portion thereof, a wheeled carriage mounted upon said rails and projecting through beneath the arched frame, a shock former supporting arm rotatably mounted upon the carriage, an extension arm carried by the supporting arm and projecting through said arcuate slot, and means to propel the said carriage forwardly and rearwardly of the harvester, the initial movement of the carriage causing the extension arm to coöperate with said arcuate slot to lower the supporting arm from a vertical to a horizontal position, and a further movement causing the carriage and extension arm to coöperate with said slidable frame to move the same forwardly to a bundle receiving position.

12. In shocking mechanism, the combination with a pair of track rails, of an arched frame slidably mounted on one of

said track rails and having an arcuate slot in the forward portion and a supporting recess in the rear portion thereof, a wheeled carriage mounted upon the track rails and 5 projecting through beneath the said frame, a supporting arm rotatably mounted upon said carriage, an extension arm fixed to said supporting arm adjacent its pivotal connection with the carriage, a brace arm fixed to 10 and extending from the outer free end of the supporting arm, and a bearing roller carried by the outer end of said brace arm and adapted to engage within the frame recess to support the outer free end of the 15 supporting arm when the latter is disposed in bundle receiving position.

13. In shocking mechanism, the combination with a self binder and harvester, of track rails disposed longitudinally thereof 20 and below the binder deck plate, an arched vertically disposed frame slidable on the outer track rail and formed with an arcuate slot, the upper end of said slidable frame being offset and rigidly secured to the movable deck plate, a wheeled carriage mounted upon said rails and projecting through beneath the arched frame, a supporting arm rotatably mounted upon said carriage, an extension arm fixed to the supporting arm 25 adjacent its pivotal connection with the carriage and projecting through said arcuate slot, and means to propel the said carriage rearwardly and forwardly of the harvester.

14. In shocking mechanism, the combination with a pair of track rails, of an arched vertical frame slidably mounted on one of said track rails and formed with an arcuate slot in the forward end portion thereof, a wheeled carriage mounted upon 30 the track rails and projecting through beneath the said frame, a supporting arm rotatably mounted upon the carriage, an extension arm fixed to the supporting arm adjacent its pivotal connection with the carriage, said extension arm projecting upwardly and adapted to project through and engage the upper end of said arcuate slot when the supporting arm is disposed horizontally, and adapted to project forwardly 35 and engage the lower rear end of the arcuate slot when the supporting arm is disposed in a vertical position, and means for propelling the said carriage in opposite directions.

15. The combination with a supporting arm, of an oblong circular cage like shock former rotatably mounted and supported by said arm, said shock former comprising a plurality of radially extending and pivotally mounted arms, superimposed separator 40 arms projected radially inwardly from each arm and designed to divide the shock former into compartments, superimposed hingedly mounted closure arms carried by each pivotally mounted arm and adapted to close the 45 entrance to each compartment, means for

opening the closure arms of each compartment prior to receiving a bundle, and means for closing each compartment immediately after receiving a bundle.

16. A shock former comprising a support, a shaft vertically movable through the support, means to limit the movement of said shaft in either direction, a housing carried by the support, a hood for a tubular supporting extension rotatably mounted in the housing, a collar fixed to said shaft and adapted to bear against the under side of said hood when the shaft is in raised position, a head block disposed within said hood and having a central bearing sleeve, the upper end of which is normally spaced from said collar, shock former arms pivotally mounted in said head block, means carried by the lower end of said shaft coöperating with said arms to hold the arms closed, and means for opening said arms when the holding means has been released.

17. A shock former comprising a support, a shaft vertically movable through the support, means to limit the movement of said shaft in either direction, a housing carried by the support, a hood having a tubular supporting extension rotatably mounted within the housing, a collar fixed to said shaft and adapted to bear against the under side of said hood when the shaft is in raised position, a head block disposed within said hood and having a central bearing sleeve, the upper end of which is normally spaced from the collar, shock former arms pivotally mounted in said head block, a cam carried by the lower end of said shaft coöperating with said arms to hold the arms closed, and means for opening said arms when the holding means has been released.

18. In a shock former, the combination with a rotatable hood, of a movable head block disposed within said hood, a vertically movable shaft disposed through said hood and head block, a cam plate carried by the lower end of said shaft, a plurality of radially disposed arms pivotally mounted in said head block, a rocker rod rotatably mounted on each arm, clamping arms mounted on one end of each rocker rod, an extension arm formed on the opposite end of each rocker rod, and a cam roller carried by each extension arm adapted to coöperate with said cam plate to open and close said clamping arms.

19. In a shock former, the combination with a rotatable hood, of a movable head block disposed within said hood, a vertically movable shaft disposed through said hood and head block, a substantially circular cam plate carried by the lower end of the vertical shaft and formed with an upstanding cam flange, said cam flange being cut away to provide an entrance opening, radially extending arms pivotally mounted in the head

block, a rocker rod embodying clamping arms rotatably mounted on each arm an extension arm carried by each rocker rod, and a cam roller carried by the extension arm 5 and adapted to bear upon the outside of the upstanding cam flange when the clamping arms are opened, and spring tension means adapted to urge said cam rollers inwardly so that they will be forced through said passage and within the circumference of said 10 upstanding cam flange to close said clamping arms.

20. In a shock former, the combination with a rotatable hood of substantially frusto-conical formation, brackets extending radially and laterally from said hood, a movable head block disposed within said hood, radially extending shock former arms pivotally mounted in said head block, a rod pivotally connected to each of said arms and extending upwardly through each supporting bracket, a bearing ball mounted on the upper end of each rod, each of said bearing balls designed to descend and rest upon each 25 bracket when the head block is moved downwardly, and serving as a fulcrum to cause said shock former arms to swing radially downwardly when a further downward movement is imparted to the head block.

30. 21. In a shock former, the combination with a rotatable hood of substantially frusto-conical formation, perforated brackets extending radially and laterally from said hood, a substantially comb shaped head block 35 disposed within said hood, means for moving said head block downwardly and upwardly, radially extending shock former arms pivotally mounted in the upper end of said head block, each of said arms being offset radially and laterally below the rotatable hood, a rod pivotally connected to each laterally offset portion of each arm and extending upwardly through the apertured bracket, a bearing ball adjustably connected 40 to the upper end of each rod, each rod together with its bearing ball being adapted to descend and rest upon its brackets when the conical head block is moved downwardly, by which movement the said arms are caused 45 to swing radially outwardly to disengage the arms from the shock.

22. In a shock former, a rotatable hood having a frusto-conical opening therein, a frusto-conical head block removably positioned within said hood, shock former arms 55 pivotally mounted in said head block, the upper portions of said arms diverging downwardly for a distance from their pivotal points, means for swinging said shock former arms radially outwardly upon the lowering of said head block, and means for raising and lowering said head block, said 60 downwardly diverging portions of the shock former arms adapted to engage and ride upwardly against the inner inclined surface of 65

said hood to force said shock former arms radially inwardly when the head block is moved upwardly within said hood.

23. In a shock former, the combination with a rotatable hood, of a head block disposed within said hood, radially extending shock former arms pivotally mounted in the head block, said arms when disposed in closed position forming an oblong circular cage, certain of said shock former arms being offset laterally and diagonally radially opposite to one another to provide a double bundle receiving space therebetween, and to provide a single bundle receiving space between said offset arms and the remaining 80 arms.

24. In a shock former, the combination with a rotatable hood, of a head block disposed within said hood, a shaft vertically movable through said hood and head block, means carried by the shaft for moving the head block downwardly, a cam plate carried by the lower end of the shaft having an upstanding peripheral flange, said cam plate adapted to move the head block upwardly, shock former arms extending radially therefrom and pivotally mounted within the head block, clamping arms carried by each shock former arm, an operating cam roller arm operatively connected to said clamping 90 arms, said cam flange being adapted to move upwardly within the circumference of the cam roller arm so that the cam rollers of said arms will be positioned exteriorly of the cam flange when the shock former arms are 100 moved radially inwardly to a closed position for the purpose set forth.

25. In a shock former, the combination with a rotatable hood of substantially frusto-conical formation, a conical head block disposed within the said hood and formed centrally with a bearing sleeve, radially extending shock former arms pivotally mounted within the head block, each of said arms being offset laterally below the hood, a circular flange carried by the head block and bearing sleeve and adapted to bear against the inner edge of each arm to hold the upper end portion of each arm against the inner surface of the rotatable hood to prevent 110 said arms from spreading, and means for moving said flange downwardly to permit the arms to swing outwardly radially.

26. In a shock former of the class described, the combination with the rotatable hood thereof and support therefor, of a ratchet wheel fixed upon said hood and formed peripherally with two sets of superimposed ratchet teeth, the upper set being formed reversely to the lower set, a head plate rotatably mounted on the hood and provided with an actuating arm, a retractile spring connected to said actuating arm, a ratchet arm extending opposite to the operating arm and adapted to engage the up- 120 125 130

- per set of the ratchet teeth, an additional head plate rotatably mounted upon the first named head plate and provided with a resetting arm disposed in the same plane with 5 said ratchet arm, means connected to said resetting arm to rotate it together with the ratchet arm to a resetting position, a trip lug carried by said resetting arm, and ratchet arms extending in opposite directions 10 from the hood support, one of said ratchet arms adapted to engage the upper set of ratchet teeth, and the other ratchet arm designed to engage the lower set of ratchet teeth, the ratchet pawl of the last 15 named ratchet arm being provided with a trip shoulder disposed in the path of the trip lug of the resetting arm, which when tripped will permit of the retractile spring to reset the ratchet.
- 20 27. In a shock former mechanism, the combination with a self binder and harvester including a needle shaft, of a shock former rotatably mounted upon the binder, ratchet mechanism mounted upon the end 25 of the shock former, a retractile spring connected to said ratchet mechanism and adapted to actuate it to cause the ratchet to rotate one step, and means connected to said ratchet mechanism and to the needle shaft of 30 the binder to reset the ratchet mechanism.
28. In a shocking mechanism of the class described, the combination with a self binder and harvester embodying a rotatable power shaft, of a carriage movably supported by 35 the binder, means for throwing the carriage into and out of gear with the power shaft, trip lugs carried by the binder and adapted to coöperate with said means to move the carriage forwardly of the binder 40 and adapted to throw the carriage out of gear with the power shaft when the carriage has reached the limit of its forward movement, trip mechanism carried by the carriage and coöoperating with the first named 45 means, a shock former rotatably mounted and supported by the carriage, and a trip arm carried by the shock former and adapted to operate the trip mechanism upon the carriage to throw the carriage into gear 50 with the power shaft when the shock former has been filled with bundles.
29. In shocking mechanism, the combination with a self binder and harvester, of a carriage movable backward and forward 55 from a bundle receiving position to a shock discharging position, a supporting arm rotatably mounted upon said carriage, a shock former embodying a plurality of radially and pivotally mounted arms, means for 60 radially opening and closing said arms,
- a trip rod operatively connected to said means, and a trip block carried by the binder and adapted to coöperate with said trip rod to radially open and close the shock former arms when the shock former is in 65 discharge position.
30. In shocking mechanism, the combination with a self binder and harvester, of a carriage movable from a bundle receiving position to a shock discharging position, a 70 supporting arm rotatably mounted upon said carriage, a shock former embodying a plurality of radially and pivotally mounted arms, means carried by the shock former for radially opening and closing said arms, a 75 trip arm pivotally mounted upon the supporting arm, a rod connecting said trip arm with the opening and closing means, and a trip plate embodying spaced arcuate flanges mounted upon the binder, one of said flanges 80 adapted to coöperate with the trip arm to open the shock former, and the other flange adapted to coöperate with the trip arm to close the shock former when in discharge position.
31. In shocking mechanism of the class described, the combination with a self binder and harvester, of a rod pivotally mounted to and depending from the knotter frame of the binder, a finger pivoted intermediate its ends to the lower end of said rod, and another rod pivotally connected to the outer end of said finger and to the knotter frame, said finger being adapted to engage the bundles as they gravitate down the 90 deck plate of the binder, the weight of each bundle being sufficient to swing the finger outwardly, which latter being pivotally mounted to swing in the arc of a circle will in its outward movement cause the bundle 95 to turn partly over for the purpose set forth.
32. In shocking mechanism of the class described, the combination with a self binder and harvester, of a shock former operatively carried thereby, and an arcuate 100 support disposed at the forward end of the binder and below the shock former, said support being adapted to support the butt ends of the bundles deposited in the shock former while the shock is being formed and 105 also to prevent the stubble from whipping the butt ends of the bundles.
- In testimony whereof we have signed our names to this specification in the presence of two subscribing witnesses.
